3 Claims. (Cl. 339—144)

The present invention relates to a means for securing the cap of an electric incandescent or discharge lamp to the envelope.

It is frequently necessary to provide such a lamp with a cap which supports the lamp so that the source of light, i.e. the heated filament or arc discharge—is accurately positioned with respect to a lens and/or reflector constituting or forming part of an optical system with which the source is to be employed. The cap is inserted into a holder, the latter being in a predetermined position to the optical system. Usually the light source is required to be located on the optical axis of the system, so that the light emergent is in the form of a focussed beam. Such an arrangement may be provided in connection with projectors for film and like transparencies, or for the headlamps of automobiles.

It is the usual practice to provide the lamp cap with a projecting flange which, when associated with a suitable mounting forming part of the holder, effects the desired location of the source. Moreover, it is necessary to ensure that the filament, or electrodes, between which the arc occurs, be accurately located with respect to the cap in order to achieve the desired result. In the generally used construction of incandescent lamp, the filament is attached to lead-in conductors supported in a glass pinch forming part of a stem which is sealed into a neck portion of the envelope of the lamp; in a gas discharge lamp, at least one of the electrodes is supported by the glass pinch. The envelope is then secured to the cap by attaching it at the neck portion to the cap with a suitable cement. Since the accuracy with which the stem can be sealed into the envelope cannot be closely controlled, optical control has to be used during the cementing stage of manufacture, to obtain the desired location of the source with respect to the holder, and to the optical system. Furthermore, when the light source is such that a large amount of heat is released, e.g. in projector lamps, it is difficult to obtain a capping cement which will not be adversely affected by the heat.

It has been proposed to secure the filament terminals of an incandescent projector lamp to tubular contacts, closed at their outer ends, which are directly sealed at their inner open ends to a pressed glass base which carries the filament and is sealed to the envelope. In this way, the tubular contacts are accurately located with respect to the filament, and being employed directly to plug into a holder and then to support the lamp in the holder, no cap or capping cement being then employed.

The object of the present invention is to provide an attachment not involving a cement between the cap and envelope of an electric incandescent or arc discharge lamp which provides accurate positioning of the light source to the cap.

According to the invention, the envelope of an electric lamp is provided with a glass base secured to the cap through the intermediary of a cylindrical metal member, sealed to the base at one end and having at least one slot therein in which is engaged a corresponding projection provided on the inner surface of the cap, the cap being of such dimensions that it closely surrounds the cylindrical member so that the filament or electrodes of the lamp are accurately positioned with respect to the cap.

2

The compositions of the metal or alloy used for the metal cylindrical member, and the glass of the base to be sealed thereto should be so chosen that their thermal expansion characteristics are substantially matched in order to avoid resultant stresses in and cracking of the glass after sealing. Conveniently, the cylindrical member is provided with, at one end, a number of projections or lugs formed integrally therewith, which are sealed into the glass base. Preferably, the lugs and slots are equiangularly displaced thereon, and in a staggered relation.

The cylindrical member is conveniently in the form of a split sleeve, and is constructed from sheet metal bent into the cylindrical form after being punched into shape. One of the projections or lugs may be divided at the split.

The projections on the inner surface of the cap may be in the form of tongues punched out of the cap and bent inwards to engage corresponding slots provided in the surface of the metal cylinder.

During manufacture, the cylindrical member, the lead wires to the filament or electrodes, and sufficient powdered glass to form the base, are placed in a suitably shaped mould, and the assembly heated to cause the glass base to fuse and be sealed to the cylindrical member and leads. Alternatively, the glass may be initially in the form of a short length of tubing. The lead wires are arranged to pass through the base when formed and the lugs or projections on the cylindrical member are located so as to simultaneously be sealed into the base, the axis of the cylindrical member being normal to the plane of the base.

A glass exhaust tube may also be located in the mould so as to be sealed to the base during the same operation. Alternatively, an aperture may be left in the base into which an exhaust tube is subsequently sealed. The lead wires passing through the base are now ready to receive the filament or electrode-supporting assembly, which is jig-mounted in the required position with reference to the glass base. After this operation, the outer envelope is sealed to the periphery of the base, and the lamp evacuated and tipped off.

The invention will now be described with reference to the accompanying drawings, in which:

FIG. 1 illustrates in elevation a projection lamp and cap assembly constructed in accordance with the invention,

FIG. 2 illustrates in perspective, the cylindrical member through which the cap is attached to the glass base,

FIG. 3 is a perspective view of the cap of the lamp before assembly, and

FIG. 4 is a part cut-away elevation of the glass base showing the manner in which the cap is attached to the glass base.

Referring to the drawings, the lamp consists of an envelope 1 containing the plane type projection filament 2 and a cap 3 secured to the glass base 4 of the envelope. The filament 2 is in the form of a number of sections arranged parallel to one another, being supported by a framework constituted of a pair of frame members 5 to which the terminals 6 of the filament are secured. The frame members 5 are attached to leading-in conductors 7 which constitute the terminal leads of the filament, into one of which may be inserted an internal fuse 8. The filament is further supported by wires 9 which are hooked to engage in the appropriate filament loop. The filament supports 9 are insulated from one another and held rigidly in position by being embedded into oppositely positioned glass beads 10. The frame members 5 are also secured to the beads 10 by wires 11 which are also embedded in the beads.

The glass base 4 of the envelope through which the leading-in conductors 7 are sealed, is of pressed-glass construction and is provided with an evacuating tubulation 12 (FIG. 4). The pressed base may be formed from molten glass tubing, or from a powdered glass moulded and sin-

tered. Leading-in conductors 7, to which the terminals of the filament are connected, pass through the base, a dummy lead 13 being also provided for the purpose of connecting to one of the frame members 5 and supporting the frame in accurate relation to the base member 4. Each lead-in conductor 7 is connected to the corresponding external contact terminals 19 of the lamp cap which are insulated from one another and from the supporting cylinder 3 by means of the insulating bead 20.

The filament 2 is mounted upon the base member 4 by way of the leads 7 and 13 in a manner such as accurately to position the filament with respect to the base member. The envelope 1, when sealed in the usual manner to the base member 4 provides an evacuable enclosure for the filament, but its position relative to the base member is comparatively unimportant provided that it is substantially symmetrically connected to the base member. Since the requirement is that the filament of the lamp, when the lamp is inserted into a holder, be accurately positioned with respect to an optical system in turn related to the position of the holder, it is essential for the base 4 to be accurately located with respect to the cap 3. This is achieved, according to the invention, without the use of cement, by using an intermediate cylindrical member 14, as shown in FIG. 2. One end of the cylindrical member 14 is sealed into the glass base 4 of the lamp, and for this purpose, the cylindrical member may be provided with projections or lug 15 at one end, formed integrally with the cylindrical surface. The cylindrical member 14 is also provided with a number of slots 16 punched into its surface, and from the surface of the cap 3 (FIG. 3), a corresponding number of tongues 17 are inwardly pressed. The cylindrical member 14 is of a diameter slightly smaller than that of the cap 3, so that when the former is inserted into the cap in the appropriate position, the tongues 17 inwardly project through the holes 16. To secure the cylindrical member and the cap together, the tongues 17 are bent around as shown in FIG. 4. Since the cylindrical member 14 is sealed into the base 4, as shown at 18, the cap is now securely attached to the base.

The cylindrical member 14 is conveniently in the form of a split sleeve, and is constructed from sheet metal bent into the cylindrical form after being punched into shape. One of the projections or lugs 15 may be divided at the split, as shown at 19.

The invention provides a firm means of attachment of the cap to the glass base, without the use of a cement or solder.

In addition to the leads 7 and 13, further members (not shown in the drawings) in the form of stubs may be sealed into the base, the purpose of the further members being to supplement the attachment between the base and the filament assembly. In this way, the filament assembly may be given increased strength against lateral displacement by cross-bracing, and another of the stub leads may form the leading-in conductor from the cap to the fuse.

With the construction illustrated, simplification in the manufacture of a pre-focussed lamp is achieved by reason

of there being no necessity for the affixing of the envelope to the cap with optically controlled accuracy.

The use of the invention does not, however, avoid the necessity for ensuring that, during manufacture, the source of light, e.g. filament or arc discharge, is accurately located with relation to the base of the lamp to which the envelope is subsequently sealed; this means that the leads supporting the filament or electrodes must be accurately positioned with respect to the cylindrical member 14. Since this can be achieved by using an accurately formed mould for the support of the parts while the base is being made, no particular difficulty arises from this requirement.

While the construction has been described more particularly with regard to a filament type projection lamp, it is evident that it may equally well be applied to a discharge lamp, in which the leads 7 may carry the electrodes between which the arc discharge takes place.

What I claim is:

1. An electric lamp comprising a base-plate of vitreous material, leads for supporting energy converting means sealed through said base, a cylindrical metal member sealed end-on to said base-plate, said member having at least one slot therein, and a cylindrical cap having integral insulated terminals attached to the energy converting means, said cap being arranged closely surrounding said member and having a projection entering said slot whereby to secure said cap to said base-plate through said member.

2. An electric lamp comprising a vitreous envelope, a base-plate of vitreous material sealed to and forming part of the envelope, leads for supporting energy converting means sealed through said base-plate, a cylindrical metal member sealed end-on to said base-plate in accurately positioned relation to said leads, said member having at least one slot therein, and a cylindrical cap having moulded-in insulated terminals attached one each to the said leads, said cap being a push fit over said cylindrical member and having a projection entering said slot whereby to lock said cap to said member, and thus to the base-plate.

3. An electric lamp comprising a vitreous envelope, a base-plate of vitreous material sealed to and forming part of the envelope, leads for supporting energy converting means sealed through said base-plate, a cylindrical metal member having lugs projecting from one edge thereof sealed into said base-plate so as accurately to locate said member with relation to said leads, said member having a plurality of uniformly spaced slots in its peripheral wall, and a cylindrical cap having moulded-in terminals attached to the respective leads, said cap closely surrounding said cylindrical member and having a plurality of projections each entering a respective slot in said cylindrical member whereby to secure said cap integrally to the lamp envelope.
